UNITED STATES PATENT OFFICE.

SKIDMORE O'HARA, OF WALTHAM, MASSACHUSETTS, ASSIGNOR TO O'HARA WALTHAM COMPANY, OF WALTHAM, MASSACHUSETTS, A CORPORATION OF MASSACHUSETTS.

MACHINE FOR PRINTING OR EMBOSsing.

Application filed May 20, 1927. Serial No. 193,038.

The invention relates to a new and useful improvement in machines for printing or embossing. It relates especially to machines in which the printing or embossing member is vertically reciprocable and has a printing surface which receives a design from a die, and then transfers the design to the work, the die and work holder being alternately brought into alignment with the printing member which is actuated to be pressed into engagement with the die and then raised and then the die is moved out from alignment therewith and the work holder containing the work is moved into alignment with the printing member which is then operated to print the work on the holder, then the printing member is raised and the work holder is withdrawn.

The invention is especially applicable to machines for printing or embossing on glass, china, porcelain, enamelled goods or other brittle or frangible articles although it is not limited to machines for printing on articles of that character.

The present invention relates especially to the means for actuating the work holder.

The invention will be fully understood from the following description when taken in connection with the accompanying drawings and the novel features thereof will be pointed out and clearly defined in the claims at the close of this specification.

In the drawings:

Fig. 1 is a fragmentary side elevation of a machine embodying the invention.

Fig. 2 is a view as viewed from the left side of Fig. 1.

Fig. 3 is a section on line 3—3, Fig. 1.

Fig. 4 is a section on line 4—4, Fig. 3.

Referring to the drawings:

There is shown at 10 a frame or casting to hold the working parts, said frame having overhanging arms 11 supporting a bearing 12 in which a plunger 13 is vertically reciprocable. Said plunger carries on its lower end a member 9 to which is secured a pad 15 of gelatin or other suitable material having a surface adapted to take ink or other printing substance from a die and adapted to transfer the design to the work when the printing pad is brought into engagement with the work. The said plunger may be operated by any suitable means for raising and lowering it. Mounted in guideways 16 in the frame is a slide 17 carrying a die 14

on which is formed the design to be printed, or embossed on the work. Said carrier is slideable in one direction to bring the die out from under the printing member in order that the die may be inked and then the carrier is moved back into operative position beneath the printing pad which is pressed into engagement with the die in order that the design may be impressed upon the pad which in turn will print the design on the work. Any suitable mechanism may be employed for this purpose. As shown in the drawings, the die carrier 17 is connected with a rack 18 which engages with a gear 19 mounted on the shaft 20 which may be driven by any suitable mechanism to rotate the said shaft on its axis alternately in opposite directions and thereby to move the said rack 18 forward and back to carry the die into position under the printing member and then to move the die back out from under the printing member when the printing member rises. An inking roll 21 is provided above the path of movement of the die so that the die will engage with the inking roll 21. The die will also pass under the wiper 22 which runs under guide rolls 23, 23 to wipe off the surplus ink.

A work holder 24 is mounted on a swinging arm 25 which near one end is mounted fast on a vertical stud 26 pivoted in a bearing 27 so that said arm 25 may swing in a horizontal plane. The work holder 24 is shown as provided with upwardly extending pins 28, 28 adapted to engage with perforations or recesses in the work to hold the work steady on the holder.

The said stud 26 carries a gear 29 which engages with a rack 30 mounted on a reciprocable slide bar 31. Said slide bar 31 also carries a rack 32 whose teeth engage with a pinion 33 mounted on shaft 20. When the shaft 20 rotates in one direction, for instance, clockwise from the position shown in Fig. 1, the gear 19 will cause the rack 18 and slide 17 to move to the right as viewed in said Fig. 1, and thereby carry the die 14 toward the right out from under the printing member 15. At the same time the rack 32 will also move toward the right carrying with it the slide bar 31 and the rack 30 which by reason of its engagement with the gear 29 will rotate the pivot stud 26 in a direction to swing the arm 25 around so as to bring the work holder 24 under the print-

ing member 15. The rotation of the shaft 20 will be so regulated as to cause the arm 25 to swing through 180° or any other predetermined arc of rotation to bring the work holder 24 directly under the printing member 15.

When the die 14 moves toward the right, it will as already described move back to the position shown in dotted lines in Fig. 1 and 10 in so doing will pass beneath the inking roller 21 and in engagement therewith so as to be inked by said roller.

Mechanism is provided for raising and 15 lowering the plunger 13 at proper intervals to successively receive the impression from the die and transfer the impression to the work on the holder. Mechanism for actuating the plunger is not shown here as it does not form a part of the present invention 20 but any suitable mechanism may be employed for the purpose to be operated either by hand or power.

What I claim is:

1. A machine of the character described 25 having a vertically reciprocable printing member, a pivotally mounted work holder adapted to be turned on its pivot into and out of alignment with the printing member, a movable die having thereon the design to 30 be printed and adapted to transfer the design to the printing surface when the die and the printing surface are brought into engagement with each other, means for moving the die into and out of alignment 35 with the printing member and means for turning said work holder to move the work into and out of alignment with the printing member.

2. A machine of the character described 40 comprising a movable die having thereon the design to be printed, a pivotally mounted work holder, a vertically reciprocable printing member having a printing surface thereon adapted to receive from the die the impression 45 of the design to be printed and adapted to transfer the said design to the work, means for vertically reciprocating said printing member, means for moving said die into and out of alignment with the 50 printing member and means for turning the work holder on its pivot to move the work into and out of alignment with the printing member.

3. A machine of the character described 55 comprising a movable die having thereon the design to be printed, a pivotally mounted work holder, a vertically reciprocable printing member having a surface thereon adapted to receive from the die the impression 60 of the design to be printed and adapted to transfer the said design to the work, means for vertically reciprocating said printing member, means for moving said die into and out of alignment with the printing 65 member, means for turning the work holder

to move the work into and out of alignment with the printing member, and means for controlling the movements of the die and work holder in such manner that they will alternately be brought into alignment with 70 the printing member.

4. A machine of the character described having a vertically reciprocable printing member, a work holder mounted on an arm pivotally mounted adjacent the path of 75 movement of the printing member, means for turning said work holder arm on its pivot to move the work mounted on the holder into and out of alignment with the printing member, a die having thereon the design to be 80 printed, a movable carrier therefor adapted to bring the die into and out of alignment with the path of movement of the printing member, said die being adapted to transfer the design to the printing member when the 85 said two members are brought into engagement with each other and means for vertically reciprocating said printing member.

5. A machine of the character described 90 having a vertically reciprocable printing member adapted to receive a design from a die and adapted to imprint said design upon the work, a work holder carried by an arm mounted upon a stud rotatable on a vertical axis whereby said work holder may be moved to bring the work into and out of alignment with the printing member, a die having the design which is to be printed and which is adapted to transfer the design to said printing member, said die being mounted upon a 95 slid able member adapted to move the die into and out of alignment with the printing member, a shaft adapted to rotate alternately in opposite directions, gear and rack connections whereby said shaft actuates said die carrier, gear and rack connections whereby 100 said shaft is adapted to rock said work holder stud on its axis and means whereby when the die is moved to operative position with relation to the printing member the work holder will be moved out of operative position and when the die is moved out of operative position the work holder will be moved into operative position.

6. A machine of the character described 105 having a vertically reciprocable printing member adapted to receive a design from a die and adapted to transfer said design to the work, a work holder carried by an arm mounted upon a rotatable stud whereby said work holder may be moved to bring the work into and out of alignment with the printing member, a die having the design which is to be 110 printed and which is adapted to transfer the design to the printing member when said two members are brought into engagement with each other, said die being mounted upon a 115 slid able member adapted to move the die into and out of alignment with the printing member, said die carrier having a rack 120

mounted thereon, a rotary shaft having a gear which engages with said rack, a gear and slide rack connection between the said shaft and the work carrier stud, said gears and racks being so arranged that when the shaft rotates in one direction the die will be moved into alignment with the printing member and the work carrier will be moved

out of alignment with the printing member and when the said shaft rotates in the reverse direction the die will be moved out from under the printing member and the work holder will be moved into alignment with the printing member. ¹⁰

In testimony whereof I affix my signature.

SKIDMORE O'HARA.
